UNITED STATES PATENT OFFICE.

ALEXANDER V. BAKER AND DANIEL M. BAKER, OF ROCKY, OKLAHOMA.

EQUALIZER.

No. 894,999.

Specification of Letters Patent.

Patented Aug. 4, 1908.

Application filed July 29, 1907. Serial No. 386,158.

To all whom it may concern:

Be it known that we, ALEXANDER V. BAKER and DANIEL M. BAKER, citizens of the United States, residing at Rocky, in the county of Washita, Oklahoma, have invented certain new and useful Improvements in Equalizers, of which the following is a specification.

This invention relates to draft appliances, and more particularly to draft equalizers, and has for its object to provide an equalizer which will be simple in structure and arrangement and which will present a combination of parts adjustable to suit different conditions.

Another object is to provide an equalizer which may be manufactured at a low figure.

Other objects and advantages will be apparent from the following description and it will be understood that changes in the specific structure shown and described may be made within the scope of the claims without departing from the spirit of the invention.

In the drawings forming a portion of this specification, and in which like numerals of reference indicate similar parts in the several views, Figure 1 is a top plan view of the present equalizer; Fig. 2 is a front elevation; Fig. 3 is a side elevation; Fig. 4 is a section on line 4—4 of Fig. 1.

Referring now to the drawings, the present invention comprises an attaching member 5 slit longitudinally from its rear end to form outer tongues 6 and an intermediate tongue 7. The outer tongues are bent upwardly to form transversely alining eyes which, with a yoke 8 engaged therebetween, receive a pivot pin 9, it being understood that the yoke is fastened to the vehicle or apparatus with which the present equalizer is used.

The intermediate tongue 7 is bent forwardly over the attaching member 5, and a transversely extending lever 10 is pivoted adjacent to one end between the tongue 7 and the attaching member, upon a pivot bolt 11. A longitudinal slot 12 is formed in the attaching member, forwardly of the lever 10 and receives a bolt 13 engaged in the rearward portion of a longitudinally extending plate 14 which is thus slidable with respect to the attaching member, and this plate has a pointed rearward end portion 15 which is arranged to fit at times into a notch 16 formed in the forward edge of the lever 10, to hold the lever against movement. The bolt 13 may be operated to hold the sliding plate 14

at different points of its movement, as will be understood. The forward end of the attaching member 5 is bifurcated, as shown at 17, and between the resultant spaced portions, a bolt 18 is slidably engaged, which is carried by the plate 14, there being thus formed a guide for the forward portion of the plate. A lever 19 is pivoted adjacent to one end upon the plate 14 and extends with its major portion at the same side of the attaching member with the major portion of the lever 10, and the outer ends of these levers 10 and 19 are connected by a pivoted link 20. A forwardly extending link 21 is hinged to the opposite end of the lever 10, this end being that adjacent to the pivot point of the lever, and the link 21 is pivoted at its forward end to a laterally extending arm 22 which alines with and is pivoted to the adjacent end of the lever 19, the pivot point of the link 21 and arm 22 being located adjacent to the pivoted end of the arm. An arm 23 is pivoted at its inner end to the forward end of the sliding plate 14, and a link 24 connects the lever 19 with the arm 23, the pivotal connection of the link with the arm being located adjacent to the inner end of the latter, and the point of connection of the link with the lever 19 being between the link 20 and the point of pivotal connection of the lever 19 with the plate 14. The arm 23 thus extends at a common side of the equalizer with the major portion of the levers 10 and 19.

Whiffletrees 24^x are connected with the outer ends of the arms 22 and 23, and it will be observed that by shifting the plate 14, the position of the pivot point of the lever 19 is varied and thus the action of the equalizer may be adjusted. To further change the action, the lever 19 may be adjusted transversely of the plate 14, the lever being provided with a plurality of openings 19' to receive the pivot bolt 14', as shown. When it is desired to lock the equalizer against operation, the plate 14 is moved to engage its rearward end in the notch 16, as will be understood.

What is claimed is:

1. In a device of the class described, the combination with an attaching member cut at one end to form a pair of outer tongues and an intervening intermediate tongue, said outer tongues being bent to form alining eyes, said intermediate tongue being bent upon the attaching member in spaced relation thereto, of a lever pivoted between said

intermediate tongue and the attaching member.

2. In a draft equalizer, the combination with a member of a lever pivoted thereupon, said lever having a notch therein, a plate slidably mounted upon the member and arranged for movement to engage one end in the notch to hold the lever against movement, elements pivotally connected with the plate and connections between said elements and the lever.

3. In a draft equalizer the combination with an attaching member, of a lever pivoted upon the attaching member, a plate slidably connected with the attaching member, means for holding the plate at different points of its movement, a lever pivoted upon the plate, an arm pivoted at one end to an end of the second lever, connections between the first and second levers, and connections between the first lever and the arm.

4. In a draft equalizer, the combination with an attaching member, of a lever pivoted upon the attaching member, a plate slidably connected with the attaching member, means 25 for holding the plate at different points of its movement, a lever pivoted upon the plate, an arm pivoted at one end to an end of the second lever, connections between the first and second levers, connections between the 30 first lever and the arm, a second arm pivoted to the plate, connections between the second lever and the second arm, and whiffletrees carried by the arms.

In testimony whereof we affix our signatures, in presence of two witnesses.

ALEXANDER V. BAKER.
DANIEL M. BAKER.
